TOOL GRINDING MACHINE AND THE LIKE

John V. Nelson, Elmhurst, Ill., assignor to
Franz K. Krag, Chicago, Ill.

Application March 29, 1945, Serial No. 585,479

4 Claims. (Cl. 51—225)

1

This invention has to do with tool grinding machines, and the like. Generally speaking, the present tool grinder is intended for use in the grinding of cutting tools, that is, tools having lateral or side cutting edges as distinguished from drilling tools, but other uses of the invention will suggest themselves to the student of this application. Furthermore, the present invention is especially intended for the grinding of tools having spiral flutes at or adjacent to the cutting edges, tools of this type being well known and widely used in the machine tool arts.

One feature of the invention is to make provision for ensuring correct and accurately controlled relation between the grinding wheel and the tool itself during the grinding operations; and in this connection to make provision for moving the tool in proper fashion with respect to the position and grinding position of the grinding wheel, at all times during movement of the tool itself with respect to the grinding wheel, or vice versa. In other words, to make provision for ensuring correct relation between the tool and the grinding wheel, and to ensure that such correctness of relation will be maintained as the tool and the grinding wheel are moved with respect to each other to bring successive portions of the tool into grinding relation to the grinding wheel.

A principal object of the present invention is to provide a form and arrangement of grinding tool which is very convenient for manual operation, and with the hand or manually operated crank by which the tool holding chuck is rotated placed directly in line with said chuck and directly operating on said chuck, so that a most direct chuck operation is secured, and one whereby a most accurate control of the grinding operation is made possible.

A further object and feature, in connection with the foregoing is to make provision for adjustment of the pitch of movement of the tool carrying chuck during the rotary movement thereof under action of such hand crank, to thereby make possible the grinding of flutes of a wide range of pitches; to make provision for the grinding of each of a plurality of flutes, all of the same pitch, and equally spaced around the periphery of the tool being treated; and to provide a very simple construction, and one which is well adapted to meet practical operating conditions as said conditions are found in the shops where such tools are used.

It is here pointed out that in order to secure longitudinal movement of the tool carrying chuck at the same time that said chuck is rotated, there

2

is provided a suitable inter-connection between the chuck rotating and the chuck traversing devices; and also, in order to vary the pitch of the flute being ground, or to make it possible to grind flutes of different pitches, means are provided for varying the ratio between rate of angular rotation of the chuck and rate of traverse of said chuck; or for varying the inverse of said ratio. When said ratio is large, that is, when the pitch of the flutes is steep, it will be seen that a large amount of traverse endwise must occur for each rotation of the chuck; and when the force for operation of the device is provided by rotation of the chuck by means of a hand crank it is seen that when said crank is subjected solely to a rotary force, so that the traversing force applied to the chuck is derived solely through the inter-connection above referred between the chuck rotating and chuck traversing devices, there is a limit to the steepness of the flutes which can be ground, depending among other things on the coefficient of friction of the operating parts, the pressure of the grinding wheel against the flute surfaces, and other factors of the device.

It is a further object of my present invention, by placing the hand crank directly in line with the chuck traverse, and with a direct connection to the chuck rotating connection, to make it possible to subject said crank to either a rotary or a pressure or pull (in the direction of chuck traverse) force, or both such forces simultaneously, so that the necessary traversing and rotary movements may be secured in all cases; sometimes by a simple rotary force, sometimes by a simple push or pull force, and sometimes by a combination of these two forces. Such latter operation will generally be found the most desirable, the operator grasping the crank handle and rotating it in the proper direction, or first in one direction and then in the other direction, and at the same time moving the handle away or pulling it towards himself, as seems necessary and according to the resistance being encountered, and according to the pitch of the flute being treated.

Other objects and uses of the invention will appear from a detailed description of the same, which consists in the features of construction and combinations of parts hereinafter described and claimed.

In the drawings:

Figure 1 shows a plan view of a machine embodying the features of the present invention;

Figure 2 shows a right-hand side elevation corresponding to Figure 1;

Figure 3 shows a left-hand side elevation corresponding to Figures 1 and 2;

Figure 4 shows a front elevation corresponding to Figures 1, 2 and 3, the flute setting pin being set into position for engagement of holes or recesses of the outside row;

Figure 5 shows a back elevation corresponding to Figures 1, 2, 3 and 4;

Figure 6 shows a bottom view of the translatory table, removed from the stand, and with the cam follower block also removed to disclose the spur gear which engages the rack on the follower block; Figure 6 is also a view taken on the lines 6-6 of Figures 2, 3, 4, 5, 7 and 12, looking in the directions of the arrows;

Figure 7 shows a cross-section on the lines 1-1 of Figures 1, 2, 3, 6, 8, 9, 10 and 12, looking in the directions of the arrows; and this figure shows the cam follower block which engages both the rotary table element and the translatory table which carries the tool chuck;

Figure 8 shows a plan view of the stand proper, with the translatory table and other parts removed; and is a view taken on the lines 8-8 of Figures 2, 3, 4, 5, 7 and 12, looking in the directions of the arrows;

Figure 9 shows a view similar to that of Figure 8, but at a higher elevation, being taken on the lines 9-9 of Figures 2, 3, 4, 5, 7 and 12, looking in the directions of the arrows;

Figure 10 shows a top face view of the rotary table, with the cam follower block in place thereon;

Figure 11 shows a bottom face view of the cam follower block removed from the rotary table, and it shows the bottom of the rack bar proper and the cam follower element turned to an angle corresponding to the angular setting of the turntable or rotary table as shown in Figure 10;

Figure 12 shows a longitudinal section taken on the lines 12-12 of Figures 1, 4, 5, 6, 7, 8, 9 and 10, looking in the directions of the arrows; the translatory table being in the central portion of its translatory travel;

Figure 13 shows a view of a cutting tool of one type for which the present machine is adapted;

Figure 14 shows an end view corresponding to Figure 13;

Figure 15 shows a face view of the form of grinding wheel which is also shown in Figure 17 hereof, and which form of grinding wheel is adapted for use in connection with the present grinding machine;

Figure 16 shows a detail section of the setting pin and arm; being a section taken on the lines 16-16 of Figures 1 and 6, looking in the directions of the arrows; and

Figure 17 is a cross-section through the form of grinding wheel shown in Figure 15; and Figure 17 may also be considered in connection with Figure 12 to show the relative positions of the grinding wheel and the tool during the grinding operation.

Referring first to Figures 1, 2, 3, 4 and 5, and others, the machine herein disclosed is conveniently carried by a base plate or block 29, which is, for convenience in construction, shown as carrying the stand portion 21. Sometimes this stand portion may be formed integrally with the base plate, as will be readily evident from further study of the present disclosures. For simplicity said base plate includes the circular or ring shaped flange 22 which receives the forward and rear legs 23 and 24 which depend from the

stand portion proper, and which carry said stand. Conveniently the base plate and the stand are provided with the central openings 25 and 26 respectively. The stand also has the upper portion 27 extending between the legs 23 and 24, which upper portion is recessed as shown at 28 to receive the circular table 29. The top face of this circular table is registered with the top face of the stand as clearly evident from Figures 7 and 12, so that both these surfaces lie in a common plane.

The top face of this table 29 is provided with the transverse channel 30, constituting a cam within which a suitable cam-follower is adapted to travel laterally of the table. The circular table is itself rotatable into any angular set position, so that the angle which the channel or cam 30 will then occupy with respect to the longitudinal axis of the stand can thus be varied into any selected and set angle.

Means are provided for conveniently turning the circular table into any selected position of setting, to thereby adjust and set the angle which the transverse cam channel 30 occupies with respect to the longitudinal axis of the machine. Evidently the translatory movement of a cam-follower travelling in said cam channel will depend on this angle of setting of the table, so that by adjusting the angle or set turned position of the table the amount of translation which will be effected by the cam-follower may be adjusted into any set amount. In other words, by this setting of the table into a selected rotary position, the ratio between lateral and translatory movements effected by a cam-follower travelling in the cam channel can be adjusted into any given setting. This ratio between lateral and translatory movements will in turn determine the pitch or length of pitch of the grinding operation, thus making possible correct calibration of the machine itself to effect correct grinding of flutes of different pitches and lengths of pitch. This will presently appear hereinafter.

To turn the turntable 29 into selected position, and to indicate the position into which it is thus turned, I have provided the wheel or circular indicator 31 connected to said turntable 29. This wheel is conveniently provided with the upwardly extending stem 32 which is journaled in a vertical bearing of the table portion 27. The upper end of this stem is connected to the turntable 29 so that these elements retain fixed relationship. This wheel 31 reaches between the legs 23 and 24, and its edge portion is visible between said legs, as shown in Figures 2 and 3. Said edge is then provided with the calibration readings 33, preferably in the form of degrees or else in readings of pitch or the like, which readings are comparable to the mark 34 on the stationary portion 27. To turn the wheel accurately, and to facilitate close calibration thereof during such turning, I have shown the holes 35 spaced around the flange of the wheel, and into which a suitable instrument, such as a pin, may be inserted to rotate the wheel to a new and selected position. Comparison of the calibration marking 33 with the fixed mark 34 will at all times inform the operator as to the rotary setting of the turntable, and therefore the setting of the cam channel with respect to the longitudinal axis of the machine.

To enable locking of the turntable in any given set position I have provided the set screw 36 which extends through the portion 27 radially 78 with respect to the turntable, and the inner end

5

of this set screw may bear against the brake block 37 (see Fig. 9) which is set into a suitable recess of the portion 27 in position to be locked against the stem 32 of the wheel, and thus to lock said wheel in its set position. Upon setting the turntable into a selected calibration position it may thus be locked during the grinding operation for which such setting has been made.

Carried by the stand, or by the upper portion 27 thereof, there is a translatory table 38 which in turn carries the tool chuck. This translatory table 38 conveniently comprises the flat portion 39 which rides on the surface of the stand portion 27, and which translatory table is provided with the edge bars 40 and 41 which engage the edge portions of the stand portion 27, and retain the translatory table thereon, while permitting free translatory movement of such table. To this end the edges of the stand portion are chamfered as well shown in Figure 7, and the bars 40 and 41 are correspondingly bevelled. Said bars are readily removably attached to the under face of the translatory table, as by the screws 42 or similar devices.

The bottom face of this translatory table is provided with the transversely extending channel 43 which receives the cam-follower or an element connected thereto. By this means proper inter-engagement is established between the translatory and rotary tables to effect translatory movement of that table in properly calibrated manner as determined at any given time by the rotary setting of the rotary table.

The cam follower is shown in detail in Figures 9, 10 and 11. It includes a rack bar portion 44 which travels in the channel 43 of the translatory table, which rack bar portion has on its top face the rack teeth 45, and to its bottom face there is pivotally connected the cam block 46 which travels in the cam channel 30 of the rotary table 29. Such pivotal connection is conveniently established by the stud 47 carried by the small plate 48 set into a recess on the bottom face of the rack bar portion 44 and secured therein in suitable manner, as by screws (not shown). It will be seen that when the translatory table is set into position above the rotary table, with the cam follower element properly engaged with both the transverse channel 43 of the translatory table and the channel 30 of the rotary table, there is effected an inter-connection between the translatory and rotary tables which will ensure a relative inter-movement of said parts, depending on the angle of setting of the rotary table at such time. Evidently when the cam channel 30 lies directly across the machine, that is, at right angles to the direction of translation, full back and forth movement of the cam follower can be effected without any motion of translation of the translatory table occurring; and conversely, when the cam channel 30 lies parallel to the direction of translation, full translation lengthwise of the machine may occur without any transverse movement occurring. Between these two extremes various combinations may be secured to an infinite number. Furthermore, it will be evident that if the moving force be a force communicated to the rack bar 45 tending to shift the same laterally or transversely of the machine, such force can be effective to cause translation of the translatory table up to an angle of the cam channel 30 with respect to the longitudinal axis of the machine, which angle is determined by the friction to be overcome in various moving parts, and also by the co-efficient of friction of the cam

6

follower with its cam channels 30 and 43, respectively. For many conditions it will be found satisfactory to depend wholly on the force of lateral movement of such cam follower delivered thereto through the rack teeth, but in other cases it may be found desirable to subject the translatory table to a force of direct translation parallel to the length of the table, as well as to the effect of the engagement of the cam follower with its respective cam channels.

The translatory table 38 is provided with a longitudinally extending bore 49 wherein is journalled a shaft which may be rotated to effect rotation of the tool carrying chuck. Such rotation then serves to rotate the tool being ground; but it is also necessary to at the same time effect motion of translation of the tool so that the grinding action will correctly follow the spiral of the flutes of the tool. Both of these movements (rotation and translation) of the tool are effected from the single movement of rotation (or translation) to which the tool is effected by corresponding movement of the control element.

The shaft just referred to is shown as the rod 50, the front end of which carries the block 51, said block being normally free to rotate on the shaft, but by tightening the set screw 52 said block may be locked to said shaft. A retainer plate 53 held to the front end of the rod 50 by the screw 54 serves to prevent this block from being unintentionally slipped off from the rod when the set screw 52 is loosened. The block 51 is provided with an enlargement 55 at one position, which enlargement is slotted to receive the end of the crank arm 56 with a nice fit. This crank arm is held in place in said slot by means of the screw 57, which when loosened permits the crank arm to be rocked slightly on said screw as a pivot but which screw when tightened serves to clamp the crank arm securely to the enlargement 55 and thus retain said crank in fixed position with respect to the block 51; the elasticity of the metal in which the slot is cut being sufficient to allow such clamping of the crank arm to be effected merely by tightening the screw 57. Said crank arm carries at its free end the crank handle 58, the detailed construction of which is shown in section in Figure 16. This will be alluded to hereinafter.

Manifestly the foregoing scheme makes it possible to rock the shaft 50 through any desired angle merely by turning the crank handle 58, or said shaft may thus be rotated through several revolutions as required to effect grinding of the entire length of the flute of the tool.

At the rear portion of the bore 49 said bore journals the tubular shaft section 59; and the rear end of said tubular shaft section is enlarged to provide the chuck head 60. This chuck head is provided with the socket 61 to receive the end of the tool to be ground, said tool being locked to the chuck head by the set screw 62. The tool itself is shown at 63, and a typical form of such tool which may be ground by this machine is shown in Figure 13. Said tool is shown as having the several spiral flutes 64, each of which has the cutting edge 65; and it is a prime purpose of the machine of the present invention to provide for accurately grinding each of these cutting edges, accurately following the spiral of the flute, and also making provision for the number of flutes and cutting edges with which the tool is provided, in the case of the illustrated tool, four.

The shaft rod 50 is drivingly connected to the shaft tube section 59 by providing a drive fit

between these two parts, the end of the rod being forced into the bore of the tube. This scheme is herein shown and has been adopted for convenience in assembling the device. Manifestly other arrangements might be substituted therefor if desired. Furthermore, I have, in Figure 12 shown the washers or gaskets 64^a and 65^a, the washer 64^a being on the tubular section 59 and serving to protect against entry of dust and the like into the interior of the bore 49 at points adjacent to the grinding position. The washer 65^a is on the tubular section 66 presently to be described, and performs a similar function of protection against entry of dust, etc., into the bore 49 adjacent to the front end of the machine.

The tubular section 66, just referred to overlies the rod shaft section 50, working within the front portion of the bore 49. The rear end portion of this tubular section 66 is provided with the pinion teeth 67 which mesh with the teeth of the rack 45 so that rotation of said tubular section 66 serves to shift the rack in one direction or the other, laterally of the table, and thus serves to effect travel of the cam follower in its respective cam channels already described.

The front end of said tubular section 66 has connected to it the disk 68, as by the screws 69. Said disk 68 is provided with a suitable bore to pass the rod shaft section 50; and in the arrangement shown said rod shaft is provided with the encircling rib or flange 70 in line with the disk 68, so that the bore of said disk is made large enough to accommodate said flange 70 as shown in Figure 12. This flange serves to thus lock the rod shaft section against endwise movement with respect to the tubular section 66, but free rotation between these parts is permitted until provision is made to prevent such free rotation. That provision I have made as will now be explained.

The crank arm 58 is provided with the spring retracted pin or stud 71, which has its rear end normally projected by the spring 12 into the position shown in several of the figures, including Figures 1, 2, 3 and 16. Said stud is provided with the head 73 which may be readily grasped and pulled outwardly to compress the spring and to draw the end 74 of said stud forwardly from the position shown particularly in Figure 16. Then, when said head is released the spring will again force the stud into the position of said Figures 1, 2, 3 and 16, projecting it fully. When so projected said end 74 of the stud will engage one of the holes provided in the disk 68 for reception of said stud end, thus locking the crank and thus also locking the head 51 and the rod shaft and the tool chuck to the said disk; and since said disk is connected to the tubular section 66 it follows that the pinion is thus also locked to the tool chuck. As a consequence, under these conditions rotation of the crank handle 58 will serve both to rotate the tool carrying chuck and also the pinion 67; and thus the rack and the cam follower will be shifted laterally at the same time that the tool is rotated by rotation of the crank.

It was previously made evident that lateral shifting of the cam follower block will serve to cause the translation table to shift longitudinally of the machine, that is, parallel to the axis of the tool carried by the chuck. Therefore rotation of the crank handle performs simultaneously both the rotation of the tool chuck and its tool, and also serves to shift said parts with a translatory movement, endwise of the tool. These combined movements will produce a spiral relation between the tool and the point of contact of the

grinding wheel with the tool surface, as will presently be made more apparent.

Now the rate of translation of the translatory table in comparison to the rate of rotation will depend on the angle at which the cam channel 30 lies with respect to the transverse plane of the machine; and by adjusting that angle by turning the wheel 31 to the proper angular position it is possible to establish any desired pitch angle and pitch length in this combined movement. Having once set or adjusted the wheel position and having once locked the crank to the disk 68, back and forth rotations imparted to the crank by the operator will serve to effect spiral movements of the tool, and by previously adjusting the wheel to the correct angle such spiral movements may be made to correspond exactly to the spirals of the flutes of the tool. Thus it is possible to bring the operations of the machine into exact registry with the requirements of the flutes already existing on the tool itself, and to ensure that the movements imparted to the tool will be correct for continuous and uniform engagement of the grinding wheel with said flutes and their cutting edges.

The foregoing explanation shows how the degree or rate of spiral movement imparted to the tool may be made to correspond to the degree or rate of spiral actually existing in the flutes of the tool; but it is evident that in order to effect correct grinding of the cutting edges of said flutes the tool carried by the chuck must also be brought to the correct angular position for any given endwise position of the tool to ensure that such spiralling movement of the tool will not only correspond to the spirals of the tool flutes, but also that contact will be established and will continue between the grinding wheel and the cutting edges of the flutes.

In Figure 12 I have shown the grinding wheel 75 in its position relative to the tool itself. The grinding wheel shown is of suitable material such as carborundum or other suitable material; and the wheel shown is of generally conical form or section, with its central web 76 carried by the driving shaft (not shown); and its edge portion 77 makes contact with the tool flute to effect the grinding action thereon. With this arrangement the grinding wheel rotates on an axis parallel to the tool axis, but evidently other relationships might be substituted if desired. The point of immediate interest to this discussion is that said grinding wheel edge makes contact with the tool flute at a fixed position in space.

By loosening the set screw 52 temporarily the crank and block 51 may be turned or rotated without effecting rotation of the tool chuck. During this action the disk 68 will be turned by the turning of the crank, thus effecting a movement of translation endwise of the tool chuck and tool; and thus the tool may be brought endwise into engagement of the cutting edge of one of its flutes with the edge of the grinding wheel. Thereupon the set screw 52 may be tightened, and thereafter the back and forth rotations of the crank will effect the spiral movements of the tool with the cutting edge of the selected flute continuously in engagement with the grinding edge of the grinding wheel.

The foregoing shows that provision has been made for effecting spiral movements of the tool chuck and tool corresponding to the actual spiral of the cutting edge of the flute; but I have also made provision for readily re-setting the machine from time to time to bring this relationship into

effect for each of the flutes of a multi-flute tool successively, as I shall now show:

These cutting tools are currently made and in use with various numbers of flutes and cutting edges, but in all these cases said flutes are equally spaced around the circumference of the tool itself. It is evident that if at any time the crank 58 be rotated through some angle while at the same time leaving the disk 68 stationary, as by dis-engagement of the stud end 74 from the hole of said disk, and if the said stud end be then re-engaged with another hole of said disk 68, a fresh relationship will be established wherein the tool has been set to a different angular position with respect to the grinding point of the grinding wheel; since the non-rotation of the disk 68 during such re-setting has permitted the tubular shaft section 66 to remain idle, and therefore there has been no movement of table translation effected during such rotation of the tool chuck and tool. To this end I have provided various holes combinations in the disk 68 so that said stud end 74 may be engaged with selected ones thereof from time to time, corresponding to the numbers of flutes existing in the various tools being ground from time to time.

I have, in the machine illustrated made provision for successively grinding the flutes of tools having the following numbers of flutes, namely, 2, 3, 4, 5, 6, 8, 10, 12, 20 and 24. The flutes of such range of tools may be in any case successively ground in very simple manner and with very simple re-setting of the crank and the stud end 74 as I shall now show:

Referring to Figure 4 there are shown the five circles 78, 79, 80, 81 and 82, drawn around the axial center of the shaft rod 50 whereon the crank arm may be rotated. Each of these circles is the positioning of a plurality of holes into any one of which the stud end 74 may be engaged when the crank arm has been brought to the proper position with respect to the block 51 by loosening the set screw 57 and thereafter re-tightening said set screw. The holes on each of these circles are uniformly spaced, so that said holes will correspond to uniformly spaced flutes of tools falling in the category of such circle. The circle 78 carries 24 holes (2 of which are hidden by the crank arm); the circle 79 carries 20 holes (2 of which are hidden by the crank arm); the circle 80 carries 4 holes; the circle 81 carries 3 holes (1 of which is hidden by the crank arm); and the circle 82 carries 2 holes (1 of which is hidden by the crank arm). By setting the crank arm to such a position that the stud end 74 may engage with holes of the category of the circle 78 (having loosened the set screw 57 for this purpose, and having then re-set said set screw after so re-setting the crank arm) it follows that when the stud end 74 is disengaged from the disk 68 said crank arm may be turned to bring the stud end successively into register with any of the holes of the category of the circle 78, and then by releasing the end of the crank arm and allowing the spring 72 to function, the stud end 74 will engage with and lock the crank arm to such hole and thus to the disk at the angular position dictated by such hole. Thus, if we are grinding a tool having 24 flutes we may, upon completing the grinding of a given flute, merely draw out the stud end from the hole, turn the crank itself a slight amount to register with another hole, and allow the stud end 74 to engage with such other hole, whereupon correct relationship will be established for grinding the next flute of such series of 24 flutes; and

thus the operation may be repeated from flute to flute, successively grinding all the flutes of the tool.

If, then we have in hand a tool having some other number of flutes, we may, if need be, loosen the set screw 57, rock the crank arm to bring the stud end 74 into registry with the proper circle, and then re-lock said set screw. Thereupon the operations may be performed for a tool of the number of flutes which may be accommodated by the category of such new circle. In this connection it is to be noted that the circle 78, having 24 holes, may be used for tools having either 6, 8, 12 or 24 flutes (skipping the proper holes when grinding tools of less than 24 flutes); the circle 79, having 20 holes, may be used for tools having either 5, 10 or 20 flutes (skipping the proper holes when grinding tools of less than 20 flutes); and the circles 80, 81 and 82, having 4, 3 and 2 holes, respectively, may be used for grinding tools of said numbers of flutes. Although there are certain numbers of flutes wherein holes of more than one circle may be used (as for example, 2 fluted tools, still the foregoing distribution of work is suggested as desirable.

Conveniently the holes are all designated by the numerals 83 for convenience. Examination of Figure 4 shows that in placing the holes in the disk 68 I have in most cases staggered the holes of adjoining categories so as to improve the clearances between the successive holes.

Considering the operation of this machine the following additional comments are in order:

Since the tool chuck with its tool must be subjected to both rotary and translatory movements to follow a given flute, the forces necessary to cause both these movements must be generated and transmitted to the said chuck. I have also pointed out that by merely turning the turntable the ratio between rate of translation (endwise of the shaft) and angular velocity may be made anything from zero to infinity; or, considering the inverse of said ratio, said inverse may be made anything from infinity to zero. It is therefore evident that if we merely subject the machine to the rotary force delivered to the crank, without also subjecting it to a translatory force, we shall be able to produce the desired rotary movements of the chuck and tool, as long as we do not set the calibration wheel 31 to such angles as would produce too fast a translatory movement. In other words, as long as the flutes are not excessively steep. In the grinding of fluted cutting edges of most tools the foregoing condition will apply, since in most cases the steepness of the flutes will be found not excessive, and both the movements can be effected merely by subjecting the crank to rotary movement.

It is, however, to be noted that when manipulating the crank 58 it is also possible to exert a pulling or pushing force on the same, so that the movements of endwise translation may be assisted in this manner, and tools having very steep flutes can thus be handled.

Sometimes it may be found desirable to make provision for exerting endwise force on the translation table independently of manipulation of the crank. In this connection it is noted that such endwise force can effect both of the movements of translation and rotation as long as the steepness of the flutes is not too small, since we now have the inverse condition from that previously considered. I have, therefore, shown in Figures 2, 3 and 4 the bracket 84 secured to the stand by suitable screws, said bracket having the later-

ally extending arm 85 with the upstanding pin or stud 86. The translatory table is provided with the upstanding pin or stud 87, so that a lever arm such as shown by the broken lines 88 (see Figure 1) may be engaged with both said studs 86 and 87 to effect back and forth or translatory movement of the table merely by swinging said lever arm back and forth.

Although the wheel 29 is shown as provided with the degree markings 33 (see Figures 2 and 3), still it is evident that other suitable markings might be substituted, as for example such markings as would directly indicate flute pitches, or other markings corresponding to the terms used in the machine tool art.

Evidently when a lever arm such as shown at 88 is used to effect back and forth or translatory movements of the translatory table suitable pin and slot connections should be provided between said lever and the studs 86 and 87 or other provision should be made for the angularity which will occur in rocking of the lever.

Examination of Figure 12 shows that the end portions of the tubular shafts 59 and 66 are of larger diameter than those portions of these shafts which lie in the central portion of the bore 49, said bore providing shoulders adjacent to the end portions, and against which the enlarged portions of the tubular shafts bear. Any endwise movement of the shaft members is thus prevented, so that the translation of the tool chuck and the tool is properly controlled. The shoulders aforesaid are shown at 89 and 90 in Figure 12.

It is also evident that movement of the table 35 endwise of the shaft should be limited to such amount as will properly grind the tool flutes, but further movement towards the free end of the tool is unnecessary; and movement in the opposite direction (towards the chuck end of the tool) should be positively limited so that the grinding action will not inadvertently be carried beyond the cutting edges of the flutes and onto the chuck portion of the tool. In Figure 1 I have shown a simple means to effect such limitations of movement of the translation table. I have there shown the bracket extension 91 carried by the base portion of the stand, and having the upstanding arms 92 and 93. The rear end of the translation table carries the plate 94 which is shown as provided with the laterally extending arm 95 which travels between the arms 92 and 93; and set screws 96 and 97 threaded through said arms 92 and 93 serve to limit the movements of the arm 95 and thus also limit the translatory movement of the table at such points as are determined by the setting of said set screws.

It will also be noted that the relation between the movements of rotation and translation depends on the relative interaction of the cam channels 30 and 43, with both of which the cam follower is engaged. When these cam channels are straight as shown in Figures 6 and 9, in particular, the ratio of rotary and translatory movements will be constant, corresponding to spirals of uniform pitch throughout the translatory movement. It is, however, evident that by specially forming one or both of said channel cams it is possible to secure a spiral movement of non-uniform character, with either an increase or a decrease of pitch of the flutes as measured from one end of the tool to the other end thereof. I therefore contemplate the use of cam channels of selected forms to meet the requirements of the flutes to be ground.

I claim:

1. In a grinding machine for rotary cutting tools having flutes located at regularly spaced positions around such tool, the combination of a translatory table, means to support said table for direct straight line translation of the table, a tool holding chuck journaled in one end portion of the table for rotation on an axis parallel to the direction of table translation, a tubular shaft element journaled in the other end portion of the table for rotation about an axis co-axial with the axis of the chuck, said tubular shaft having inner and outer ends, a pinion in connection with the inner end portion of the tubular shaft, a rack element in meshing engagement with said pinion, there being a trackway in the table for said rack element extending in a direction non-parallel to the rotational axis of the tool holding chuck and the tubular shaft, a turntable journaled in the supporting means adjacent to the translatory table for angular adjustment about an axis substantially intersecting the axis of rotation of the tool holding chuck and the tubular shaft, a trackway in the turntable, a turntable slide working in said trackway, a companion trackway in the rack element, a rack element slide working in the rack element trackway, a pivotal connection between the turntable slide and the rack element slide, whereby movements of translation of the translatory table and movements of rotation of the tubular shaft are conjointly effected in proportion dependant on the angular adjustment of the turntable, the tool holding chuck including a shaft extension extending through the tubular shaft to a position adjacent to the outer end of the tubular shaft away from the pinion, an indexing disk secured to the outer end of one of the shaft elements, said indexing disk being provided with a series of uniformly angularly spaced indexing holes, an indexing crank secured to the outer end of the other shaft element, and a pin element in connection with the crank element and engageable with a selected one of said series of indexing holes, whereby said crank may be manipulated by an operator to exert both rotational and translatory forces on the crank to thereby subject the shaft elements to rotational forces and to translatory forces simultaneously to thereby effect combined movements of rotation of the shaft elements and corresponding translatory movements of the shaft elements and the table element for all angular positions of adjustment of the turntable, the tool holding chuck being located at that end of the device opposite to the position of the indexing disk and the indexing crank, whereby rotational movements of the crank are effected without interference from the tool holding chuck and a tool carried thereby, substantially as described.

2. A device as defined in claim 1, wherein the indexing disk is secured to the outer end of the tubular shaft and the indexing crank is secured to the outer end of the tool holding chuck shaft extension, substantially as described.

3. A device as defined in claim 1, wherein the indexing disk is provided with a plurality of series of uniformly angularly spaced indexing holes, and wherein the indexing crank is engageable with the holes of any one of said series as selected, substantially as described.

4. A device as defined in claim 1, wherein the indexing disk is secured to the outer end of the tubular shaft and the indexing crank is secured to the outer end of the tool holding chuck shaft extension, and wherein the indexing disk is pro-

13

vided with a plurality of series of uniformly angularly spaced indexing holes, and wherein the indexing crank is engageable with the holes of any one of said series as selected, substantially as described.

JOHN V. NELSON.
